DYEING APPARATUS FOR TEXTILE
PACKAGES

Ernest A. Stienen, Peekskill, N. Y.

Application April 9, 1949, Serial No. 86,501

3 Claims. (Cl. 68—198)

1

My invention relates to apparatus for dyeing yarn in package form, particularly to spindles for supporting packages during the dyeing process, and has for its primary object to provide an improved spindle which is capable of increasing the volume of dye liquor therethrough and thus enable more units to be dyed per spindle.

It has been the practice heretofore, as far as applicant is aware, to provide a perforated hollow spindle having an open socket at one end for attachment to a perforated cylinder of a dye carrier and at the other end a cap for sealing the liquor, so that flow thereof is directed longitudinally along the open socket and spindle, thence transversely through the perforations of the spindle and tube on which the cap is wound, and finally through the wound yarn. It has been known also to provide a fin type spindle, cross shaped in transverse section as indicated in Drum et al. Patent 2,306,719 of December 29, 1942, for supporting packages during the dyeing process. However, in these conventional spindles the volume of liquor flow therethrough is restricted to the internal open area of the spindles. In the hollow perforated spindle the total available area is limited by the internal diameter thereof and, since the perforated tubes carrying the packages are superposed thereupon, the thickness of the perforated spindle is the limiting factor. In the fin type spindle the thickness of the material comprising the cross shaped fins limits the area available for liquor flow.

Accordingly, it is another object of my invention to overcome the above disadvantages by providing a greater area for liquor flow in the supporting spindle and also at the socket end of the spindle.

With the above objects in view, an embodiment of my invention discloses a spindle assembly comprising a solid rod in threaded engagement with a tapered socket having a solid end portion in which the rod is secured and a longitudinal bore with transverse peripheral openings for passage of dye liquor therethrough. The socket is threaded on its external surface for removable attachment to the shell of a dye carrier and at its inner end is provided with a seat for a perforated tube on which a package of yarn is wound. The longitudinal bore of the socket is at least equal to the inner diameter of the perforated tube while the total cross-sectional area of the transverse peripheral openings is greater than that of the perforated tube or socket bore, thereby greatly increasing the volume of liquor that may be introduced into the spindle.

2

According to a feature of my invention advantages are secured over the prior spindles by providing in my spindle assembly a separable socket and rod, so that upon ineffectiveness of the rod it is merely necessary to replace the rod and not the socket as well, thus resulting in substantial savings.

For a more complete understanding of the nature and scope of my invention, reference may be had to the following detailed description taken in conjunction with the accompanying drawing in which:

Fig. 1 is a sectional elevational view of my improved spindle for dyeing yarn in package form;

Fig. 2 is a sectional view of the same taken along line 2—2 of Fig. 1 in the direction of the arrows; and

Fig. 3 is another sectional view taken along line 3—3 of Fig. 1 in the direction of the arrows.

Referring now to the drawing, particularly to Fig. 1, there is shown a spindle assembly 10 comprising an elongated rod 11 and a socket 12 removably attached to a dye carrier plate 13, which latter is of conventional configuration and well known in the dye art.

The outer peripheral surface 14 of the socket 12 is threaded for mesh engagement with a threaded opening 16 in the carrier plate 13 and I prefer to make this peripheral surface slightly tapered, as shown, so that the end portion 17 thereof may be readily passed through and thus extend beyond the plate 13 for a purpose that will appear hereinafter. The socket end portion 17 is shown provided with a threaded, longitudinal bore 18 for mesh engagement with the threaded end 19 of the rod 11, which also includes a shoulder 21 for limiting the depth to which the rod may be inserted into the socket. It is to be noted, therefore, that the end portion of the socket acts as a closure when the rod is assembled thereto. Inwardly of this closure is formed a longitudinal bore 22, the diameter of which is at least equal to the inner diameter of a conventional perforated tubular member 23 upon which a package 24 is wound. As shown in Fig. 1, the inner diameters of the tube 23 and bore 22 are substantially equal, so that the walls thereof are in alignment.

Intermediate the end portion 17 and the plate 13 are shown a plurality of transverse openings 26 in communication with the bore 22 and, as seen in Figs. 1 and 2, these openings are equally spaced around the peripheral surface 14 and extend longitudinally a predetermined distance.

The total entrance cross-sectional area, as represented by the sum of the individual openings 26, is arranged to be greater than the cross sectional area of the bore 22 or tube 23 minus the cross sectional area of the rod 11 in order to provide, as mentioned hereinbefore, for increased liquor flow therethrough.

This increased liquor flow will be readily apparent from the following mathematical comparison between a conventional spindle assembly having a perforated tubular spindle and the spindle of my invention. A conventional perforated rayon cake tube, such as tube 23 in the drawing, has an inner diameter of $\frac{33}{32}$ ". In my spindle the spindle rod 11 is $\frac{1}{4}$ " in diameter, which is sufficiently strong to support the required number of wound packages 24. In the prior art perforated spindle tube the inner diameter thereof is $\frac{1}{2}$ ", and it is to be noted that in conventional practice the inner end of this tube is open and the dye liquor enters through this opening and, since the other opening is closed, the liquor is forced through the perforated openings in both tubes and thence through the wound package, as is well known.

The areas of the various parts are as follows:

1. 0.40574 sq. in. for $\frac{33}{32}$ " perforated tube 23
2. 0.04909 sq. in. for $\frac{1}{4}$ " spindle rod 11
3. 0.19635 sq. in. for $\frac{1}{2}$ " perforated spindle of prior art

The difference,

$$0.40574 - 0.04909 = 0.35665 \text{ sq. in.}$$

represents the net cross-sectional area available for liquid flow in my arrangement; and, since the total cross-sectional area for liquor flow in the prior art spindle is 0.19635 sq. in., the difference, $0.35665 - 0.19635 = 0.16030$ sq. in., represents the greater amount of cross-sectional area available for liquor flow, which area is almost double that heretofore possible.

In view of the increased volume of liquor flow available through the socket of my invention it is thus possible to install more than the conventional three packages and still maintain a satisfactory flow condition.

At the other or front end of the socket 12 is shown an enlargement 27 having a plurality of angularly disposed, side faces 28 in the form of a hexagon for facilitating, by use of a suitable tool, attachment of the socket to the carrier plate. The enlargement 27 is also provided at its front face 29 with a recess 31, the wall of which is arcuate in outline and which begins at the front face 29 and continues rearwardly and inwardly, as shown, to the bore 22. The recess 31 is thus particularly adapted to seat the perforated tube 23 coaxially with respect to the spindle rod 11, as shown in Fig. 3, whether the spindle is mounted vertically or horizontally.

The assembly of the spindle to the carrier plate 13 is a simple and straightforward operation requiring merely the rotational movement of the socket 12 until it is firmly secured in the threaded opening 16, as shown in Fig. 1, after which the elongated rod 11 is inserted into the threaded opening 18 of the socket 12. Once the spindle is in position the perforated tubes 23 carrying the packages 24 are mounted thereon with the innermost tube 23 centrally disposed in the recess 31. To assure a coaxial arrangement of all superposed tubes I provide a spacer 32, having a recess 33, similar to recess 31, on opposing faces thereof, between each pair of tubes 23 and also a similar self-centering recess on a threaded cap

34 for sealing, and a nut 36 securing the entire assembly together on the spindle rod 11.

From the foregoing description, it will be seen that my invention provides a simple, practical spindle which is formed of parts that can be economically manufactured, easily handled, and can be conveniently used. Further, with my invention it is now possible to substantially increase the flow of dye liquor and thereby process more packages in the same period. Also, repair of a bent spindle is readily effected by mere replacement of the spindle rod 11.

As various changes may be made in the form, construction and arrangement of the parts herein, without departing from the spirit and scope of the invention and without sacrificing any of its advantages, it is to be understood that all matters are to be interpreted as illustrative and not in any limiting sense.

What I claim is:

1. A spindle assembly for removably connecting a package wound on a perforated tube to a carrier comprising, in combination, a socket having a longitudinal bore and a plurality of transverse openings adjacent one end thereof for passage of liquid serially therethrough, the total cross-sectional area of said transverse openings being at least equal to the cross-sectional area of said longitudinal bore, said one end of said socket being solid and having a centrally disposed threaded opening therein in axial alignment with said bore, the other end of said socket being formed with an enlarged portion greater than the diameter of said perforated tube and having on its front face a centrally disposed recess with an arcuate wall sloping inwardly from said face continuously to the bore, the diameter of said bore being uniform from said transverse openings to said recess, whereby full flow of the liquid is obtained through said transverse openings and bore, and a rod having a threaded end for mesh engagement with said threaded opening in said one end, said rod and arcuate recess being disposed in coaxial relationship with respect to each other.
2. A spindle assembly for removably connecting yarn wound on a perforated tube to a carrier comprising, in combination, a hollow socket having an externally tapered and threaded peripheral surface for threaded attachment to said carrier, and a rod with a threaded end centrally disposed in said socket, said socket having a longitudinal bore of at least the same diameter as the inner diameter of said perforated tube and adjacent one end thereof having a plurality of transverse openings for passage of liquid serially therethrough, the total cross-sectional area of said transverse openings being at least equal to the cross-sectional area of said longitudinal bore, said one end of said socket being solid and having an axially threaded bore for mesh engagement with the threaded end of said rod, said end and transverse openings being adapted to be disposed to one side of said carrier, the other end of said socket being adapted to be disposed on the other side of the carrier and being formed with an enlarged portion greater than the diameter of said perforated tube, said other end having a centrally disposed recess on its front face with an arcuate wall sloping inwardly from said face continuously to the longitudinal bore for axial disposition of said perforated tube thereon, the diameter of said bore being uniform from said transverse openings to said recess, whereby full flow of the liquid is obtained through said trans-

verse openings and bore into the perforated tube, and means connected at the other end of said rod for removably securing the perforated tube and yarn to the other end of the socket.

3. A socket for a dye spindle adapted for removably connecting a package wound on a perforated tube to a carrier comprising a tapered body with external threads for threaded attachment to the carrier, said body having a longitudinal bore and a plurality of transverse openings intermediate the ends of the socket for passage of liquid serially therethrough, the total cross-sectional area of said transverse openings being at least equal to the cross-sectional area of said longitudinal bore, one end of said body being solid and having a threaded bore therein in axial alignment with that of said bore for threaded engagement with a dye spindle rod, the other end of said tapered body being formed with an enlarged portion greater than the diameter of said perforated tube

5

10

15

20

and having on its front face a centrally disposed recess with an arcuate wall sloping inwardly from said face continuously to the longitudinal bore, the diameter of said bore being uniform from said transverse openings to said recess, whereby full flow of the liquid is obtained through said transverse openings and bore.

ERNEST A. STIENEN.
